LOOPER - THREAD CONTROLLING MECHANISM FOR SEWING MACHINES

Park A. Herr, Hillside, N. J., assignor to The Singer Manufacturing Company, Elizabeth, N. J., a corporation of New Jersey

Application August 19, 1932. Serial No. 629,416

14 Claims. (Cl. 112—241)

This improvement relates to a thread controlling mechanism for sewing machines, more particularly of the chain-stitch type, and has for its object to provide a controlling device for the lower thread which will accomplish the delivery and the taking up of the lower thread to and from the looper so that the thread will be under control at all times.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a partial side elevation of the sewing machine, with the bed partly in section, and the needle in the position where it throws out a loop for entry by the looper. Fig. 2 is a plan view of the same, with the upright standard in section, and Figs. 3 and 4 are perspective details of the oscillatory thread-controlling members. Fig. 5 is a sectional view of the thread-controlling members on the line 5—5, Fig. 1.

In the preferred form of the invention illustrated, the sewing machine frame comprises a bed 1, an upright standard 2, and overhanging head 3 in which the reciprocating needle-bar, carrying the needle 4, and the presser-bar 5, are mounted. The presser-foot 6, carried by the presser-bar, cooperates with a suitable four-motion feed-dog 7 which operates through the usual slotted throat-plate 8 let in the cloth-plate or work-support 9. It will be observed the upright standard 2 joins the bed 1, close to the line of seam formation represented by the position of the needle 4 affording only a minimum of space for working parts beneath the work-support 9.

Cooperating with the needle 4, below the throat-plate 8 is the looper 10 having the heel 10^a and the blade 11. The looper 10 is mounted upon a carrier 12 whose lower end is journaled upon the pin 13 projecting forwardly from the split hub 14 clamped upon the rock-shaft 15 suitably journaled in bearing supports 16, 16 in the bed 1. The looper-carrier 12 is retained upon the pin 13 by the collar 17 clamped thereon by screws 18. Fixed upon the rock-shaft 15 by the clamp-screw 19 is the forked arm or connection 20 straddling the slide-block 21 embracing an eccentric 22 fixed upon the main shaft 23 suitably

journaled in the bed 1. The eccentric 22 and the described connections therewith operate to rock the shaft 15 thereby imparting sidewise or so called "needle-avoiding" movements to the looper 10.

The looper derives its loop-seizing or endwise movements through a train of connections including a link 24 connecting the ball stud 25 on the looper-carrier 12 with a similar ball stud at the upper end of the arm 26 of a bell-crank lever fulcrumed at 27 upon the bed 1. The other arm 28 of the bell-crank lever is connected by a pitman 29 with a crank formed upon the main shaft 23.

The present looper-thread control is of the oscillatory type whereby the danger of winding up the looper-thread is avoided. Owing to the limited space between the looper and the junction of the bed and upright standard, the looper-thread control must necessarily be very compact. Mounted upon the driving connection or forked-arm 20 between the main shaft 23 and looper rock-shaft 15, is one element 30 of the looper-thread control comprising coacting thread-engaging elements preferably of the thread-guide and thread-cam type. In the form illustrated the member 30 is the thread-guide member and is in the form of a fork, the arms of which are apertured at 31 to receive the looper-thread *t*. The shank of the thread-guide 30, is secured upon the connection 20 by the fastening screw 32, and partakes of its oscillatory movements.

Cooperating with the oscillating thread-guide 30 is the oscillating thread-cam 33 having the active portion or hump 34 which passes between the arms of the fork 30. The thread-guides 31 and thread-cam 34 are in juxtaposed cooperative relationship, that is, the thread runs directly from one to the other, without engaging an intervening thread-guide of any sort. The shank of the thread-cam is seated in a recess formed upon the follower 35 whose upper end embraces an eccentric 36 fast upon the main shaft 23 from which it receives its operative movements. The lower end of the follower 35 is forked to embrace a guide-block 37 loosely journaled upon the looper rock-shaft 15.

In threading the machine the looper-thread *t* is led from the source of supply through the guide-eye 38 in the washer 39 thence between the tension disks 40 and thence through a second guide-eye 41 formed in a depending arm 42 of the washer 39. It will be observed that the guide-eye 41 is disposed below the work-support or plate 9 and is substantially at the level of the

looper-blade 11. From the guide-eye 41 the looper-thread passes directly to the eyes 31 in the arms of the fork constituting the thread-guiding member 30 and thence to the eye in the 5 closely adjacent looper-blade 11. It will thus be seen that the looper-thread passes in a direct and straight path from the guide-arm 42 of the tension device to the looper-blade without deviating from its course which insures a free and 10 unobstructed movement of under thread except where it is acted upon by the thread-controlling elements which are disposed closely adjacent the heel of the looper and work in planes transverse to the direction of its loop-seizing and shedding 15 movement to control the looper-thread.

It will be observed by reference to Fig. 5 that the path of movement described by the 20 thread-eyes 31 in the arms 30 is in the arc of a circle represented by the dotted lines *a* described about the fixed axis of the looper rock-shaft 15 as a center, while a point on the active portion 34 of the thread-cam describes the orbital path of movement around a field represented by the dotted ellipse *b*.

25 The operation of the device is substantially as follows:—Starting in the position of the parts shown in Fig. 1, the looper is in its forward or loop-seizing movement and is about to enter the needle-thread loop. In its forward 30 stroke the looper draws thread from its source of supply through the thread-eyes 38 and 41 and tension device 40. During this time the forward edge 34^a of the thread-cam 34 is only slightly out of alignment with the eyes 31 of the thread-guide 30 which assists the looper in its thread-drawing action, the thread riding over the central hump of the cam just before the time that the looper-blade has completed its loop-seizing movement. In the retractive movement of the 35 looper the hump 34 of the cam is traveling along the upper portion of its elliptical path in the direction of the arrow, Fig. 5, the thread being in engagement with the rear edge 34^b of the cam and the thread-eyes 31 moving in the opposite 40 direction about the circular arc *a* away from the edge 34^b. This insures a rapid take-up action on the looper-thread to take up the slack between the eye of the looper and the last 45 stitch during the first part of the retracting motion of the looper. The looper thread is thus kept closely under control so that the point of 50 the descending needle may, with certainty, enter the triangle formed by the looper-thread, looper-blade and needle-loop which is around the looper-blade at this time. This prevents buckling of the looper-thread and insures proper position of the looper thread-loop preparatory to the next descent of the needle.

60 By the means described, correct formation of the stitches is accomplished without the use of additional pull-off or nipping devices acting upon the lower-thread.

The invention is not to be understood as limited to the precise construction and arrangement of parts shown and described as various modifications within the scope and spirit of the invention will be suggested to those skilled in the art from the foregoing disclosure.

Having thus set forth the nature of the invention, what I claim herein is:—

70 1. A looper-thread controlling mechanism for sewing machines comprising a shaft, an eccentric mounted upon said shaft, an eccentric follower, a thread-cam carried by said follower, spaced thread-guides on opposite sides of and

cooperating with said thread-cam and a second eccentric on said shaft connected to oscillate said thread-guides for controlling the slack in the looper-thread.

2. A looper-thread controlling mechanism for 80 sewing machines comprising a shaft, an eccentric mounted upon said shaft, an eccentric follower, a thread-cam carried by said follower, a second eccentric mounted upon said shaft adjacent said first eccentric, a follower therefor, a thread-guide carried by said follower and actuated by said second eccentric said thread-guide being mounted in juxtaposed cooperative relationship with the said thread-cam for controlling the slack in the looper-thread.

25 3. A looper-thread controlling mechanism for 85 sewing machines comprising a shaft, an eccentric mounted upon said shaft, an eccentric follower, a second eccentric mounted upon said shaft, and a thread-guide actuated by said second eccentric, said eccentric being relatively timed to move said thread-cam and thread-guide simultaneously in opposite directions.

4. A looper-thread controlling mechanism for 90 100 sewing machines comprising a main shaft, a looper, a looper supporting shaft, a connection between said shafts for imparting operative movements to said looper, a thread-guide carried by said connection, and a movable thread-cam actuated by said main shaft and cooperating with said thread-guide for controlling the slack in the looper-thread.

5. A looper-thread controlling mechanism for 110 sewing machines comprising a main shaft, a needle and a cooperating looper, a movable forked arm having spaced thread-eyes, an oscillatory thread-controlling arm disposed between said spaced thread-eyes, and independent means for imparting relative movements to said forked 115 arm and thread-controlling arm for controlling slack in the looper-thread.

6. A looper-thread controlling mechanism for 120 sewing machines, comprising a needle and a cooperating looper, a movable arm having 125 spaced thread-eyes, a thread-controlling arm movable around a field in a plane disposed between said thread-eyes, and means for imparting relative movements to said arms for controlling the slack in the looper-thread.

7. A looper-thread controlling mechanism for 130 sewing machines comprising a main shaft, a looper rock-shaft, a looper carried thereby, a connection between said main and rock-shafts closely adjacent said looper for imparting operative movements to the latter, spaced arms having thread-eyes carried by said connection, and means disposed between said looper and said connection cooperating with said spaced arms for controlling the slack in the looper-thread.

8. In a sewing machine in combination, a main shaft, a needle, feeding mechanism, a looper, a looper rock-shaft, a connection between said shafts parallel with the line of feed for imparting operative movements to said 140 looper, an arm carried by said connection and provided with spaced thread-eyes, and an oscillatory thread-arm cooperating with said thread-eyes for controlling the slack in the looper-thread.

9. In a sewing machine, in combination, an upright standard, a work-support, a feeding mechanism, a looper with an apertured blade and means for actuating the same, a thread tension on the upright standard, a thread-guide 150

- on the upright standard disposed below the level of the work-support, a main-shaft, a thread-controlling device comprising relatively movable thread-engaging members disposed in juxtaposed cooperative relationship below the work-support and at the level of the looper-blade for controlling the slack in the looper-thread, and independent operative connections between said main-shaft and said thread engaging members. 5
10. A sewing machine having a reciprocating needle, a thread-carrying looper, means for imparting loop-seizing and shedding movements to said looper, and a looper-thread controller comprising a pair of independently timed oscillatory thread-engaging members closely adjacent the heel of the looper and working differentially in planes transverse to the direction of loop-seizing and shedding movement of the looper whereby the thread is led directly from the controller to the looper. 15
11. A looper-thread controller comprising cooperating oscillatory thread-cam and thread-guiding devices, one of said devices having a fixed axis of oscillation and the other of said devices having an orbital oscillatory movement 20 said thread-guiding devices being located relative to said thread-cam to hold the thread in position to be acted upon by said thread-cam, and separately timed actuating means for operating said devices in timed relation to one another. 25
12. A thread-controlling mechanism for sew- 30
- ing machines comprising a shaft, a pair of eccentrics mounted upon said shaft, a follower for each of said eccentrics and a pair of coacting thread-engaging devices each carried by its respective follower for controlling slack in the 80 sewing thread. 35
13. A thread-controlling mechanism for sewing machines comprising a shaft, a pair of eccentrics mounted upon said shaft, a follower for each of said eccentrics and a pair of coacting thread-engaging devices each carried by a respective follower, one of said thread-engaging devices being mounted to move around a field and the other of said thread-engaging devices being adapted to movably position the 85 thread suitably to be acted upon by the first mentioned thread-engaging device in its movement around said field. 90
14. A thread-controlling mechanism for sewing machines comprising a shaft, a pair of eccentrics mounted upon said shaft, a follower for each of said eccentrics and a pair of coacting thread-engaging devices each carried by a respective follower, one of said thread-engaging devices being mounted to move around a field 100 and the other of said thread-engaging devices being mounted to move in an arcuate path and position the thread suitably to be acted upon by the first mentioned thread-engaging device 105 in its movement around said field. 110
